UNITED STATES PATENT OFFICE.

GEORGE R. LONG, OF WATERBURY, CONNECTICUT, AND HENRY G. CORDLEY, OF GLEN RIDGE, NEW JERSEY.

LIQUID-DISPENSING DEVICE.

Application filed January 14, 1921, Serial No. 437,352. Renewed July 13, 1923.

To all whom it may concern:

Be it known that we, GEORGE R. LONG and HENRY G. CORDLEY, citizens of the United States, residing, respectively, at Waterbury, in the county of New Haven and State of Connecticut, and Glen Ridge, in the county of Essex and State of New Jersey, have invented certain new and useful Improvements in Liquid-Dispensing Devices, of which the following is a description, reference being had to the accompanying drawings, forming a part hereof.

Our invention relates to liquid dispensing devices and has for its object to provide a device adapted to dispense syrups, fruit juices and other flavoring liquids from the original bottle or container in measured quantity to be diluted with carbonated or other water for beverage purposes, which will be simple and strong in construction, readily assembled and disassembled for cleaning or other purposes, and not liable to get out of order. A further object of our invention is to provide a device for the purpose stated which will be adapted to be supported on the edge of a table or counter so as to be in convenient position for use by the beverage dispenser and will be so constructed as to take up no more space along the table or counter than is required by the diameter of the bottle or other container from which the flavoring liquid is supplied so that a considerable number of the devices, each for a different flavoring liquid, may be arranged in easy reach of the beverage dispenser. A further object of the invention is to provide a device for the purpose described from which the measured quantity of liquid may be drawn by the beverage dispenser with one hand by pushing the glass or other receptacle into position to receive the flavoring liquid.

With the objects above explained and other objects hereinafter explained in view our invention consists in the construction and combination of elements hereinafter described and claimed.

Referring to the drawings;

Figure 1 is a vertical central sectional view from front to rear, of a liquid dispensing device embodying our invention;

Figure 2 is a side elevation of the same including the supporting means;

Figure 3 is a front elevation of the device as shown in Figure 2;

Figure 4 is a partial vertical sectional view on line 4—4 of Figures 1 and 2;

Figure 5 is a vertical sectional view of the faucet on a plane passing through the axis of the turning plug, the parts being shown assembled;

Figure 6 is a view similar to Figure 5 but showing the cap, casing and turning plug disassembled;

Figure 7 is a vertical cross sectional view on line 7—7 of Figure 5; and

Figure 8 is an end view of the turning plug.

Figures 5 to 8 inclusive are on a larger scale than the other figures.

In the drawings 1 indicates the base plate of the dispensing device formed of a single piece of metal preferably by casting and provided in its rear portion on its upper face with a cylindrical seat 2 for the open lower end of container 3, preferably of glass, and is also provided on its upper face forward of the seat 2 for the container, with a cylindrical seat 4 for the open lower end of a measuring vessel 5. On its lower face below the seat 4 the base plate 1 is provided with a downwardly extending portion which forms the casing 6 of the faucet, having formed therein a tapered seat adapted to receive the turning plug 7. On its lower face below the seat 2 for the container 3 the base plate is provided with a seat 8 to receive the forwardly extending portion 9 of a supporting arm 10.

The upper face of the base plate within the seat 2 for the container 3 is preferably inclined downward towards the front of the device and at the centre of its front is formed an opening or port 11 leading to the interior of the casing 6, through which the contents of the container will flow to the seat for the turning plug. The seat 2 is preferably screwthreaded at 12 to receive the screwthreaded lower end of the container 3 and, below the screwthread is formed a shoulder 13 to receive a gasket 14 on which the lower end of the container rests when in position and which serves to prevent leakage.

The seat 4 for the measuring vessel 5 is screwthreaded to receive the lower screwthreaded end of the measuring vessel. Through the portion within the seat 4 is formed an opening or port 15 leading to the interior of the casing. The measuring ves-

sel has a closed top 16 preferably milled on its edge as shown to enable it to be readily rotated to cause its screwthreads to be engaged and disengaged with the screwthreads 5 of its seat. Through this top 16 extends a vent pipe 17.

The casing 6 is provided in its lower face about in line with the centres of the container 3 and measuring vessel 5 with a discharge port or opening 18. Within the tapered seat formed in the casing 6 fits the tapered turning plug 7 having formed through it at right angles to its axis an opening or port 19 the lower end of which is adapted to be brought into and out of register with the discharge port 18 by rotation of the turning plug. The upper end of this opening or port 19 terminates in a recess 20 extending across the turning plug at right angles to its axis and of such length that when the turning plug is in normal, that is, in closed position, with the lower end of its port 19 out of register with the discharge port 18, the recess 20 will connect the end of port 11 with the end of port 15 so that liquid will flow from the container 3 to the measuring vessel, and when the turning plug is rotated to open position, that is, to bring the lower end of its port 19 into register with the discharge port 18, the recess 20 with the port 19 will form an open passage for liquid to flow from the port 15 of the measuring vessel to the discharge port.

On the upper end of the container 3 rests a ring 21 the upper portion of which is curved to form a seat 22 for a ring 23 of rubber or other resilient material adapted to serve as a support for the shoulder of an inverted bottle 24, which will ordinarily be the bottle in which the fruit juice or other flavoring liquid is received from the manufacturer. Into the open upper end of the vent pipe 17 is inserted a pipe 25 the upper end of which is bent over and inserted in an opening 26 formed to receive it in the ring 21 so that any liquid which may be forced up the vent pipe 17 and pipe 25 will be conducted back into the container.

As liquid is drawn into the measuring vessel 5 the air contained in it passes freely up the vent tube 25 into the container 3. When the faucet is so turned as to permit the liquid to flow from the measuring vessel, air will pass down the vent tube from the container sufficient air leaking past the ring 23 to prevent any exhaustion of the air within the container.

The turning plug 7 is provided on one end, the right hand end in Figure 3, with an operating handle comprising a radial, downwardly extending portion 28 from the lower end of which a portion 29 extends laterally beneath the casing 6 so that when

the turning plug is in closed position, that is, with its port 19 out of register with the discharge port 18, this laterally extending portion of the operating handle is directly below the discharge port. At its other end the turning plug is provided with a spring, constructed and arranged as hereinafter described or otherwise, by which it is held normally in closed position and by which it is returned to closed position when the operating lever is released.

When the turning plug is in closed position liquid flows freely from the container to the measuring vessel until it is filled to the level of the liquid in the container which will be the level of the mouth of the bottle 24, the liquid filling the measuring vessel and extending upward into the vent pipe 17. In order to draw the liquid contained in the measuring vessel into the glass 30, or other receptacle, it is only necessary to push the glass against the laterally extending portion 29 swinging the operating lever rearward rotating the turning plug till its port 19 is in register with the discharge port 18. The measured quantity of liquid in the measuring vessel then flows into the glass. When the glass is removed the turning plug is returned to closed position by the spring cutting off flow of liquid from the measuring vessel but permitting liquid to flow from the container into the measuring vessel to refill it.

The construction and arrangement of the spring device for rotating the turning plug to closed position is preferably that described and claimed in the application for Letters Patent of the United States filed by us December 1, 1920, Serial No. 427,560, and comprises an abutment 31 at the inner end of the tapered seat formed in the casing to receive the turning plug, having a central opening 32 with a ring 33 surrounding and extending rearward from it, and a shoulder 34 surrounding the base of the ring with a seat 35 about the base of this shoulder. Through the ring 33 and opening 32 extends inward toward the turning plug a cylindrical projection 36 carried by the cap 37 having flange 38 with its edge resting against the seat 35. The cylindrical projection 36 has an opening through it the inner portion of which is adapted to receive a central projection 40 on the inner end of the turning plug 7 which is flattened on one side or is otherwise made non-circular in cross section. The outer portion of the opening through the cylindrical projection 36 is circular in cross section and is of greater diameter than the inner portion so as to leave a shoulder 41 between the inner and outer portions. In this outer portion of the opening through the cylindrical projection 36 is received the head of a screw 42 which engages a screwthreaded opening 130

in the end of the projection 40 on the turning plug and serves to hold the cap and turning plug together. A spring 44 is coiled about the ring 33 between it and the interior 5 of the flange 38, with one end secured to the casing at 45 and the other end secured to the cap at 46, this spring being constructed to press the cap outward away from the casing 6 and also to rotate the 10 cap, and with it the turning plug, in a direction to rotate the port 19 out of register with the discharge port 18, and to resist rotation of the turning plug in a direction to bring the port 19 into register with the 15 discharge port.

In the flange 38 of the cap is formed a slot 48 of sufficient length to permit of the necessary movement of rotation of the turning plug, into which slot extends a stop pin 20 49 carried by an arm 50 secured to the under side of the base plate 1.

From this description it will be understood that the spring 44 serves to hold the turning plug normally in closed position 25 with the operating handle in the position in which it is shown in Figure 2, and also serves to return the turning plug to normal position as soon as the glass 30 pushed against the laterally extending portion 29, 30 is removed.

The supporting arm 10 is arranged at the rear of the base plate 1 with its upper portion 9 extending forward, as above described beneath the base plate. At its lower 35 end the supporting arm 10 is provided with a rearwardly extending portion 52 which is secured by a thumbscrew 53 on the upper arm of a clamp 54 through the lower arm of which extends a clamping screw 55 40 adapted to bear against the under side of a table 56 or like support.

By reason of this construction of the support the dispensing device may be secured to the rear edge of a table or counter 45 so as to be in easy reach of the person dispensing beverages and, as the device takes up along the edge of the table or counter only the space required to accommodate the bottle 24, the operating handle for the faucet 50 extending beneath the base plate within the lines of the side edges of the base plate, a considerable number of these dispensing devices may be arranged together along the 55 edge of the table or counter so as to provide for a variety of flavoring liquids. The supporting arm 10 being arranged at the rear of the base plate ample space is afforded for the rearward swing of the operating arm of the faucet. When, as is the usual 60 arrangement in dispensing beverages, the faucet for the carbonated water is arranged between syrup dispensing devices, the person dispensing the beverages may use one hand to control the faucet for the carbonated water and may with the other hand,

by pushing the glass against the laterally extending portion 29 of the operating arm, draw the required amount of the particular flavoring liquid desired and then carry the glass to the carbonated water faucet. By 70 thus obviating the necessity of removing one hand from the carbonated water faucet the operation of dispensing is facilitated and a material saving of time effected.

It will of course be understood that we 75 do not desire to be limited to the particular construction and arrangement of parts shown and described as it is evident that many of the details shown and described may be varied without departing from the 80 spirit of our invention.

Having thus described our invention what we claim is;

1. In a dispensing device, a base plate 85 having the rear portion of its upper face adapted to receive a liquid container, having the front portion of its upper face adapted to receive a measuring vessel, and having on its lower face below the portion which receives the measuring vessel, a faucet casing integral with said base plate having a seat for a turning plug, ports leading from the container and measuring vessel to the seat for the turning plug, and a discharge 90 port leading downward from the seat, and a 95 turning plug in said seat having an operating handle provided with a laterally extending portion below the faucet.

2. In a dispensing device, a base plate 100 having the rear portion of its upper face adapted to receive a liquid container, having the front portion of its upper face adapted to receive a measuring vessel, and having on its lower face below the portion which receives the measuring vessel, a faucet casing 105 having a seat for a turning plug, ports leading from the container and measuring vessel to the seat for the turning plug, and a discharge port leading downward from said seat, a turning plug in said seat having an operating handle provided with a laterally extending portion below the faucet, and a support for the base plate at its rear.

3. In a dispensing device, a base plate 110 having the rear portion of its upper face adapted to receive a liquid container, having the front portion of its upper face adapted to receive a measuring vessel, and having on its lower face below the portion which receives the measuring vessel, a faucet 115 casing having a seat for a turning plug, ports leading from the container and measuring vessel to the seat for the turning plug, and a discharge port leading downward from the seat, a turning plug in said seat 120 having an operating handle provided with a laterally extending portion below the faucet, and having a port extending transversely through it, and a spring arranged to hold the turning plug normally with its 125 130

transverse port out of register with the discharge port.

4. In a dispensing device, a base plate having the rear portion of its upper face adapted to receive a liquid container, having the front portion of its upper face adapted to receive a measuring vessel, and having on its lower face below the portion which receives the measuring vessel, a faucet casing having a seat for a turning plug, ports leading from the container and measuring vessel to the seat for the turning plug, and a discharge port leading downward from the seat, a turning plug in said seat having an operating handle provided with a laterally extending portion below the faucet, and having a port extending transversely through it, a spring arranged to hold the turning plug normally with its transverse port out of register with the discharge port, and means carried by the base plate for limiting the rotation of the turning plug.

5. In a dispensing device, a base plate having on the rear portion of its upper face a seat for the open lower end of a liquid container, having on its upper face forward of the seat for the container, a seat for the open lower end of a measuring vessel, and having on its lower face below the seat for the measuring vessel, a faucet casing having a seat for a turning plug, having ports leading from the seats, for the container and measuring vessel to the seat for the turning plug and a discharge port leading downward from the seat, a liquid container having its lower end secured in its seat, a measuring vessel having its lower end secured in its seat, and a vent tube leading from the measuring vessel into the container.

6. In a dispensing device, a base plate having on the rear portion of its upper face a seat for the open lower end of a

liquid container, having on its upper face 45 forward of the seat for the container, a seat for the open lower end of a measuring vessel, and having on its lower face below the seat for the measuring vessel, a faucet casing having a seat for a turning plug, having 50 ports leading from the seats for the container and measuring vessel to the seat for the turning plug and a discharge port leading downward from the seat, a liquid container open at both ends having its lower end secured in its seat and having its upper end adapted to receive and support an inverted bottle, a measuring vessel closed at its upper end having its lower end secured in its seat, and a vent tube leading 55 from the closed upper end of the measuring vessel into the container.

7. In a dispensing device, a base plate having the rear portion of its upper face adapted to receive a liquid container, having the front portion of its upper face adapted to receive a measuring vessel, and having on its lower face below the portion which receives the measuring vessel, a faucet casing having a seat for a turning plug, ports leading from the container and measuring vessel to the seat for the turning plug, and a discharge port leading downward from said seat, a turning plug in said seat having an operating handle provided 70 with a laterally extending portion below the faucet, and a support for the base plate at its rear consisting of an upwardly extending arm having its upper portion extending forward beneath and secured to the 75 base plate and provided at its lower end with means for securing it to a table or counter.

In testimony whereof we affix our signatures this 9th day of December, 1920.

GEORGE R. LONG.
HENRY G. CORDLEY.
